UNITED STATES PATENT OFFICE.

SAMUEL SEGAL, OF NEW YORK, N. Y., ASSIGNOR TO SEGAL METAL PRODUCTS COMPANY, INC., OF NEW YORK, N. Y., A CORPORATION OF DELAWARE.

DESIGN FOR A LOCK CASING.

60,379.

Specification for Design.

Patented Feb. 7, 1922.

Application filed August 10, 1921. Serial No. 491,231. Term of patent 14 years.

To all whom it may concern:

Be it known that I, SAMUEL SEGAL, a citizen of the United States, residing at New York city, in the county and State of New York, have invented a new original, and ornamental Design for a Lock Casing, of which the following is a specification, reference being had to the accompanying drawing, forming part thereof, in which—

Fig. 1 is a front elevation of a lock casing showing my new design.

Fig. 2 is an end view thereof.

Fig. 3 is a top plan view thereof.

I claim:

The ornamental design for a lock casing as shown.

SAMUEL SEGAL.
